[57] CLAIM

The ornamental design of the child's exerciser/rocker, as shown and described.

DESCRIPTION

FIG. 1 is a perspective view of a child's exerciser/rocker showing our new design;

FIG. 2 is a top plan view thereof;

FIG. 3 is a right side view thereof;

FIG. 4 is a front view thereof;

FIG. 5 is a bottom view thereof; and,

FIG. 6 is a rear view thereof.

The left side view is a mirror image of the right side view.
